UNITED STATES PATENT OFFICE.

ELWARD B. SOMERS, OF DARBY, PENNSYLVANIA, ASSIGNOR TO TYBON CORPORATION, OF CAMDEN, NEW JERSEY, A CORPORATION OF NEW JERSEY.

DESIGN FOR A CASING FOR A RIBBON-REWINDING MACHINE.

Application filed March 23, 1928. Serial 25,969. Term of patent 14 years.

To all whom it may concern:

Be it known that I, ELWARD B. SOMERS, a citizen of the United States, residing at Darby, in the county of Delaware and State of Pennsylvania, have invented a new, original, and ornamental Design for Casing for a Ribbon-Rewinding Machine, of which the following is a specification, reference being had to the accompanying drawing, forming part thereof.

Figure 1 is a perspective view, Figure 2 is a side elevation and Figure 3 is a top plan view of a casing for a ribbon rewinding machine, showing my new design.

I claim:

The ornamental design for a casing for a ribbon rewinding machine as shown.

ELWARD B. SOMERS.
